CLAIM

The ornamental design for a kettle lid with handle, as shown and described.

DESCRIPTION

FIG. 1 is a top, front, right side, perspective view of a kettle lid with handle;

FIG. 2 is a front elevation, the rear elevation view being a mirror image thereof;

FIG. 3 is a left-side elevation view, the right-side elevation view being a mirror image thereof;

FIG. 4 is a top plan view thereof;

FIG. 5 is a bottom plan view thereof;

FIG. 6 is a cross-section view thereof, taken along Line 6-6 of FIG. 2;

FIG. 7 is a top, front, right side, perspective view thereof, shown with environment;

FIG. 8 is a top, front, right-side perspective view thereof, shown with a gasket installed and as unclaimed matter; and,

FIG. 9 is a top, front, right-side exploded perspective view thereof, shown with a gasket as unclaimed matter.

The broken lines depict portions of the kettle lid and additional environmental structure, such as the kettle body in FIG. 7 and gasket in FIGS. 8 and 9, that form no part of the claimed design.
